UNITED STATES PATENT OFFICE.

PETER G. VAN WIE, OF PIQUA, OHIO, ASSIGNOR TO THE FAVORITE STOVE AND RANGE COMPANY, OF SAME PLACE.

GAS-STOVE.

SPECIFICATION forming part of Letters Patent No. 602,041, dated April 5, 1898.

Application filed August 27, 1895. Serial No. 560,681. (No model.)

To all whom it may concern:

Be it known that I, PETER G. VAN WIE, residing at Piqua, in the county of Miami and State of Ohio, have invented certain new and 5 useful Improvements in Gas-Stoves, of which the following is a specification.

This invention relates to gas-stoves, and has for its object to provide in a gas-stove having a closed compartment in its upper portion a tubular air-supply flue communicating at its lower end with the atmosphere through the side of the stove and projecting at its upper end into the said compartment, an annular gas-burner being secured upon the upper 15 discharge end of the flue and having a gas-supply pipe and a deflector-plate arranged centrally within the burner.

To this end my invention consists in the construction and the arrangement and combination of parts hereinafter described, and particularly pointed out in the claim following the description.

The features of my invention are more fully set forth in the description of the accompanying drawings, making a part of this specification, in which—

Figure 1 is a central vertical section through a series of combustion-chambers of my stove. Fig. 2 is a top plan view of one of the burners. Fig. 3 is a central vertical section of Fig. 2.

E represents the air-supply passage in which the burner is located. This passage communicates with the atmosphere at its lower end through the wall of the stove and thence is curved upward and terminates in the combustion-compartment. The burner F is located in the top of this air-passage and is supplied with gas through pipe K. The 35 burner is preferably formed of the two sections g, united by annular joints, and the pipe K is preferably integral with one of the sections.

j represents the burner-orifices, which are 40 shown in full line in the section h, Fig. 3. The burner may be used the other side up, in which case the orifices are drilled in section i.

l represents the stove-lid, preferably made

of two sections, the upper being an annular 50 plate and the inner section being a circular plate, so as to use boilers of different sizes.

M represents a deflector-plate preferably slightly below the orifices j and centrally located relative to the burner. This serves to 55 distribute the air uniformly around the burner-ring and cause a thorough mixture of the gas and air. In practice these orifices are drilled at a slight angle, so as to direct the gas and air toward a common center and so 60 form a cone of flame.

H represents a broiler-compartment located between the two end combustion-compartments, as shown in Fig. 1. H' represents the burners for said compartment located under 65 the perforated plate or cover R.

S represents a central offtake-flue above the broiler. Each compartment has a flue-offtake leading to a common off-take at the rear of the stove.

I provide the joint g in the burner-sections h i with grooves d', so as to form an air-tight joint by the use of packing or cement applied to the face of the joint. The burner-orifices may be drilled vertically, if desired, in which 75 case the ring n is employed to guide the air and gas inward, as shown in dotted lines, Fig. 3.

3 represents the lugs upon which the broiler-gratings are supported.

It will be evident that any number of burner-compartments or combustion-chambers can be employed in one stove and the said compartments variously located to suit the different uses, each burner being substantially 85 the counterpart of the other, located in an air-passage and provided with an offtake-flue leading to a common offtake. By this construction the oven, broiler, and top heating-surfaces of an ordinary stove may be employed in a closed gas-stove, a perfect combustion maintained therein, and, in short, the advantages of the gas-stove combined with the advantages of an ordinary cooking stove or range, which is a great improvement 90 over the previous art.

Having described my invention, I claim—

The combination with a closed gas-stove

having a closed compartment in its upper portion, of a tubular air-supply flue communicating at its lower end with the atmosphere, through the side of the stove, and projecting 5 at its upper end into said compartment, an annular gas-burner secured upon the upper, discharge end of said flue, a gas-supply pipe for supplying gas to said burner, and a de-

flector-plate arranged centrally within the burner, substantially as specified. ¹⁰

In testimony whereof I have hereunto set my hand.

PETER G. VAN WIE.
